UNITED STATES PATENT OFFICE.

GEORGE W. WELLS, OF AMESBURY, MASSACHUSETTS; ASSIGNEE TO POWOW MANUFACTURING COMPANY, OF AMESBURY, MASSACHUSETTS, A CORPORATION OF MASSACHUSETTS.

EYE SHADE FOR MOTOR-CAR DRIVERS.

Application filed December 8, 1921. Serial No. 520,962.

To all whom it may concern:

Be it known that I, GEORGE W. WELLS, a citizen of the United States, resident of Amesbury, in the county of Essex and State 5 of Massachusetts, have made a certain new and useful Invention in Eye Shades for Motor-Car Drivers; and I declare the following to be a full, clear, and exact description of the same, such as will enable others 10 skilled in the art to which it appertains to make and use the invention, reference being had to the accompanying drawings, and to letters or figures of reference marked thereon, which form a part of this specification.

15 Figure 1 is an edge view of the invention as applied.

Figure 2 is a face view of the invention.

Figure 3 is a central longitudinal section of the same partly broken away.

20 Figure 4 is a section on the line 4-4 of Figure 3.

The invention has relation to means for shading the eyes of the drivers of motor cars when suddenly driving into the sunlight, or when driving at night facing strong lights, especially in the rain, an object being to provide an improved eyeshade, attachable to the bottom of the forward edge portion 25 of the roof of a closed car or to the lower face of the front bow of the top of an open car, the attachment being in both cases upon the inside of the car, and the device being foldable out of the way to a position parallel with the roof or top of the car.

30 The invention consists in the novel construction and combinations of parts, as hereinafter set forth.

In the accompanying drawings, illustrating the invention, the numeral 1 designates 35 vertical end brackets, having horizontal top flanges wherein are provided perforations 2 for vertical screws or bolts 3, whereby the brackets are secured to the forward portion of the roof or top of the car, each bracket being provided with a horizontal frusto-conical extension 4 engaging similarly formed recesses 5 of plugs 6, one of which is secured in place within each end portion of a cylindrical enlargement 7 of 40 the eyeshade 8.

The plugs 6 are horizontally perforated at 45 and engaged with said perforations and passing through the hollow cylindrical enlargement 7 of the eyeshade is a hinge rod

10, one end of said rod being externally 50 threaded at 11 and having engagement with the internal thread of a perforation or recess 12 of one of the frusto-conical extensions 4, and the other end of the rod engaging the perforation 9 of the other plug 60 and terminating at the smaller end of the frusto-conical recess thereof and having an internally threaded recess 13, a screw 14 engaging the same and the horizontal perforation of the other extension 4, which perforation is extended through the related bracket 1 and enlarged therat to receive the 65 head of the screw.

The enlargement 15 of the aforesaid perforation is made sufficiently deep to receive 70 a coiled spring 16, against which the head 17 of the screw bears to compress the same and hold it under tension, the result being that the screw is prevented from being adjusted to cause too tight a wedging engagement of the frusto-conical extensions 4 with the frusto-conical recesses of the plugs, the tensioned spring bearing against the head of the screw also serving to hold the screw 75 in position as adjusted.

The end brackets 1 are stationary, and the plugs 6 are fast to the hinge enlargement of the eyeshade, whereby when the eyeshade is grasped by the hand of the operator and adjusted to the proper angle for shading 80 purposes, or folded back or upwardly out of the way, the frusto-conical recess walls of the plugs will have frictional engagement with the frusto-conical walls of the extensions 4. In this way the eyeshade will be 85 held in position as adjusted and rattling of the parts will be prevented. Any wear may be taken up by adjustment of the screw 14.

The device is of simple nature, capable of economical manufacture, readily assembled 90 and taken apart, and being attachable interiorly of and adjustable within the interior of the car, is especially convenient for the operator or driver.

I claim:

In an eyeshade for motor car drivers, vertical end brackets attachable to the tops and roofs of cars and having frusto-conical horizontal extensions one of which has a threaded recess and the other of which has a perforation one end of which is enlarged, a hinge rod having a threaded end engaging said threaded recess and at its other end

100

105

having a threaded recess, a screw engaging said perforation and the threaded end of said recess of said rod, a coiled spring seated in the enlarged portion of said perforation and bearing against the head of said screw, and a horizontal shade mounted upon said hinge rod and having end plugs provided with frusto-conical recesses engaging said

extensions, said shade being foldable to a position parallel to the said tops and roofs. 10

In testimony whereof I affix my signature in presence of two witnesses.

GEORGE W. WELLS.
